(57) **ABSTRACT**

A turbine vane platform sealing assembly, a turbine vane, and a gas turbine are proposed. The turbine vane platform sealing assembly includes a first sealing member inserted into a first groove formed in a turbine vane platform in a first direction, the first sealing member extending in the first direction, a second sealing member inserted into a second groove formed in a second direction intersecting the first direction of the turbine vane platform such that an end thereof contacts an upper surface of the first sealing member, and a third sealing member provided so as to partially extend in the first direction while being partially bent in the second direction at a point where the first and second sealing members are in contact so that at least a portion of the bent part is inserted into the second sealing member to restrict the movement of the third sealing member.

TURBINE VANE PLATFORM SEALING ASSEMBLY, AND TURBINE VANE AND GAS TURBINE INCLUDING SAME

CROSS REFERENCE TO RELATED APPLICATION

The present application claims priority to Korean Patent Application No. 10-2022-0158215, filed on Nov. 23, 2022, the entire contents of which are incorporated herein for all purposes by this reference.

BACKGROUND

1. Technical Field

The present disclosure relates to a turbine vane platform sealing assembly, and a turbine vane and a gas turbine each including the same.

2. Description of the Related Art

A turbine is a mechanical device that obtains a rotational force by an impulsive force or reaction force using a flow of a compressible fluid such as steam or gas. A turbine includes a steam turbine using a steam and a gas turbine using a high temperature combustion gas.

Among them, the gas turbine is mainly composed of a compressor, a combustor, and a turbine. The compressor is provided with an air inlet for introducing air, and a plurality of compressor vanes and compressor blades, which are alternately arranged in a compressor housing.

The combustor supplies fuel to the compressed air compressed in the compressor and ignites a fuel-air mixture with a burner to produce a high temperature and high-pressure combustion gas.

The turbine has a plurality of turbine vanes and turbine blades disposed alternately in a turbine housing. Further, a rotor is arranged to pass through the center of the compressor, the combustor, the turbine and an exhaust chamber.

Both ends of the rotor are rotatably supported by bearings. A plurality of disks is fixed to the rotor so that the respective blades are connected and a drive shaft such as a generator is connected to an end of the exhaust chamber.

Since these gas turbines have no reciprocating mechanism such as a piston in a 4-stroke engine, so that there are no mutual frictional parts like piston-cylinder, the gas turbines have advantages in that consumption of lubricating oil is extremely small, amplitude as a characteristic of a reciprocating machine is greatly reduced, and high speed operation is possible.

Briefly describing the operation of the gas turbine, the compressed air in the compressor is mixed with fuel and combusted to produce a high-temperature combustion gas, which is then injected toward the turbine. The injected combustion gas passes through the turbine vanes and the turbine blades to generate a rotational force, which causes the rotor to rotate.

The foregoing is intended merely to aid in the understanding of the background of the present disclosure, and is not intended to mean that the present disclosure falls within the purview of the related art that is already known to those skilled in the art.

SUMMARY

Accordingly, the present disclosure has been made keeping in mind the above problems occurring in the related art,

2

and an objective of the present disclosure is to provide a turbine vane platform sealing assembly capable of preventing accidental detachment from a turbine vane platform to improve reliability and operability during gas turbine maintenance, and a turbine vane and a gas turbine each including the same.

In an aspect of the present disclosure, there is provided a turbine vane platform sealing assembly including: a first sealing member inserted into a first groove formed in a turbine vane platform in a first direction, the first sealing member extending in the first direction; a second sealing member inserted into a second groove formed in a second direction intersecting the first direction of the turbine vane platform such that an end thereof contacts an upper surface of the first sealing member; and a third sealing member provided so as to partially extend in the first direction while being partially bent in the second direction at a point where the first and second sealing members are in contact so that at least a portion of the bent part is inserted into the second sealing member to restrict the movement of the third sealing member.

The first direction may be an axial direction of a gas turbine, and the first sealing member may be formed in a shape corresponding to that of the first groove.

The second direction may be a radial direction with respect to an axis of a gas turbine, and the second sealing member may be formed in a shape corresponding to that of the second groove.

The second sealing member may include a plate-shaped sealing body formed with a first thickness, and a sealing head formed with a second thickness greater than the first thickness and having an insertion groove formed in a portion connecting with the sealing body.

The third sealing member may include: an extension part formed to extend in a first direction and disposed on an upper surface of the first sealing member; a bent part formed by bending in a second direction at a point where the first sealing member and the second sealing member contact; and a protruding tab formed to protrude from an upper surface of the bent part and formed in a shape corresponding to the insertion groove.

The sum of the thickness of the sealing body and the thickness of the bent part may be the same as the second thickness of the sealing head.

The turbine vane platform may be a turbine vane outer platform coupled to an outer end of a turbine vane.

The turbine vane platform may be a turbine vane inner platform coupled to an inner end of a turbine vane.

In another aspect of the present disclosure, there is provided a turbine vane fixedly mounted within a housing by a turbine vane outer platform coupled to an outer end thereof and a turbine vane inner platform coupled to an inner end thereof, wherein at least one of the turbine vane outer platform and the turbine vane inner platform includes a turbine vane platform sealing assembly, the turbine vane platform sealing assembly including: a first sealing member inserted into a first groove formed in a turbine vane platform in a first direction, the first sealing member extending in the first direction; a second sealing member inserted into a second groove formed in a second direction intersecting the first direction of the turbine vane platform such that an end thereof contacts an upper surface of the first sealing member; and a third sealing member provided so as to partially extend in the first direction while being partially bent in the second direction at a point where the first and second sealing members are in contact so that at least a portion of the bent

part is inserted into the second sealing member to restrict the movement of the third sealing member.

The first direction may be an axial direction of a gas turbine, and the first sealing member may be formed in a shape corresponding to that of the first groove.

The second direction may be a radial direction with respect to an axis of a gas turbine, and the second sealing member may be formed in a shape corresponding to that of the second groove.

The second sealing member may include a plate-shaped sealing body formed with a first thickness, and a sealing head formed with a second thickness greater than the first thickness and having an insertion groove formed in a portion connecting with the sealing body.

The third sealing member may include: an extension part formed to extend in a first direction and disposed on an upper surface of the first sealing member; a bent part formed by bending in a second direction at a point where the first sealing member and the second sealing member contact; and a protruding tab formed to protrude from an upper surface of the bent part and formed in a shape corresponding to the insertion groove.

The sum of the thickness of the sealing body and the thickness of the bent part may be the same as the second thickness of the sealing head.

In a still another aspect of the present disclosure, there is provided a gas turbine including: a compressor configured to suck and compress external air; a combustor configured to mix fuel with the compressed air from the compressor and combust a mixture of the fuel and the compressed air; and a turbine having turbine blades and turbine vanes mounted therein, the turbine blades being rotated by combustion gases from the combustor, wherein the turbine vanes each are fixedly mounted within a housing by a turbine vane outer platform coupled to an outer end thereof and a turbine vane inner platform coupled to an inner end thereof, wherein at least one of the turbine vane outer platform and the turbine vane inner platform includes a turbine vane platform sealing assembly, the turbine vane platform sealing assembly including: a first sealing member inserted into a first groove formed in a turbine vane platform in a first direction, the first sealing member extending in a first direction; a second sealing member inserted into a second groove formed in a second direction intersecting the first direction of the turbine vane platform such that an end thereof contacts an upper surface of the first sealing member; and a third sealing member provided so as to partially extend in the first direction while being partially bent in the second direction at a point where the first and second sealing members are in contact so that at least a portion of the bent part is inserted into the second sealing member to restrict the movement of the third sealing member.

The first direction may be an axial direction of a gas turbine, and the first sealing member may be formed in a shape corresponding to that of the first groove.

The second direction may be a radial direction with respect to an axis of a gas turbine, and the second sealing member may be formed in a shape corresponding to that of the second groove.

The second sealing member may include a plate-shaped sealing body formed with a first thickness, and a sealing head formed with a second thickness greater than the first thickness and having an insertion groove formed in a portion connecting with the sealing body.

The third sealing member may include: an extension part formed to extend in a first direction and disposed on an upper surface of the first sealing member; a bent part formed

by bending in a second direction at a point where the first sealing member and the second sealing member contact; and a protruding tab formed to protrude from an upper surface of the bent part and formed in a shape corresponding to the insertion groove.

The sum of the thickness of the sealing body and the thickness of the bent part may be the same as the second thickness of the sealing head.

According to the embodiment, the turbine vane platform sealing assembly is prevented from being accidentally detached from the turbine vane platform to improve reliability and operability during gas turbine maintenance.

BRIEF DESCRIPTION OF THE DRAWINGS

FIG. 1 is a partially cut-away perspective view of a gas turbine according to an embodiment of the present disclosure;

FIG. 2 is a cross-sectional view illustrating a schematic structure of a gas turbine according to an embodiment of the present disclosure;

FIG. 3 is a partial cross-sectional view illustrating an internal structure of the gas turbine according to an embodiment of the present disclosure;

FIG. 4 is a cross-sectional view illustrating a turbine vane outer platform with a conventional turbine vane platform sealing assembly installed thereon;

FIG. 5 is a perspective view illustrating a turbine vane platform sealing assembly according to an embodiment of the present disclosure;

FIG. 6 is a side view illustrating the turbine vane platform sealing assembly according to the embodiment of the present disclosure;

FIG. 7 is a perspective view illustrating a second sealing member of the turbine vane platform sealing assembly;

FIG. 8 is a perspective view illustrating a turbine vane platform sealing assembly installed on a turbine vane platform according to an embodiment of the present disclosure;

FIG. 9 is a cross-sectional view illustrating a turbine vane platform sealing assembly installed on a turbine vane outer platform according to an embodiment of the present disclosure; and

FIG. 10 is a cross-sectional view illustrating a turbine vane platform sealing assembly installed on a turbine vane inner platform according to an embodiment of the present disclosure.

DETAILED DESCRIPTION

Hereinafter, exemplary embodiments of the present disclosure will be described in detail with reference to the accompanying drawings. However, it should be noted that the present disclosure is not limited thereto, and may include all of modifications, equivalents or substitutions within the spirit and scope of the present disclosure.

Terms used herein are used to merely describe specific embodiments, and are not intended to limit the present disclosure. As used herein, an element expressed as a singular form includes a plurality of elements, unless the context clearly indicates otherwise. Further, it will be understood that the term "comprising" or "including" specifies the presence of stated features, numbers, steps, operations, elements, parts, or combinations thereof, but does not preclude the presence or addition of one or more other features, numbers, steps, operations, elements, parts, or combinations thereof.

Hereinafter, preferred embodiments of the present disclosure will be described in detail with reference to the accompanying drawings. It is noted that like elements are denoted in the drawings by like reference symbols as whenever possible. Further, the detailed description of known functions and configurations that may obscure the gist of the present disclosure will be omitted. For the same reason, some of the elements in the drawings are exaggerated, omitted, or schematically illustrated.

FIG. 1 is a partially cut-away perspective view of a gas turbine according to an embodiment of the present disclosure, FIG. 2 is a cross-sectional view illustrating a schematic structure of a gas turbine according to an embodiment of the present disclosure, and FIG. 3 is a partial cross-sectional view illustrating an internal structure of the gas turbine according to an embodiment of the present disclosure.

As illustrated in FIG. 1, a gas turbine **1000** according to an embodiment of the present disclosure includes a compressor **1100**, a combustor **1200**, and a turbine **1300**. The compressor **1100** includes a plurality of blades **1110** radially installed. The compressor **1100** rotates the blade **1110** so that air flows while being compressed by the rotation of the blade **1110**. The size and installation angle of the blade **1110** may vary depending on the installation location. In one embodiment, the compressor **1100** is connected directly or indirectly to the turbine **1300**, and receives a portion of the power generated from the turbine **1300** to rotate the blade **1110**.

Air compressed by the compressor **1100** flows to the combustor **1200**. The combustor **1200** includes a plurality of combustion chambers **1210** and a fuel nozzle module **1220** arranged in an annular shape.

The gas turbine **1000** includes a housing **1010** and a diffuser **1400** which is disposed on a rear side of the housing **1010** and through which a combustion gas passing through a turbine is discharged. A combustor **1200** is disposed in front of the diffuser **1400** so as to receive and burn compressed air.

Referring to the flow direction of the air, a compressor **1100** is located on the upstream side of the housing **1010**, and a turbine **1300** is located on the downstream side of the housing **1010**. A torque tube **1500** is disposed as a torque transmission member between the compressor **1100** and the turbine **1300** to transmit the rotational torque generated in the turbine **1300** to the compressor **1100**.

The compressor **1100** is provided with a plurality (for example, 14) of compressor rotor disks **1120**, which are fastened by a tie rod **1600** to prevent axial separation thereof.

Specifically, the compressor rotor disks **1120** are axially arranged, wherein the tie rod **1600** constituting a rotary shaft passes through substantially central portion thereof. Here, the neighboring compressor rotor disks **1120** are disposed so that opposed surfaces thereof are pressed by the tie rod **1600** and the neighboring compressor rotor disks do not rotate relative to each other.

A plurality of blades **1110** are radially coupled to an outer circumferential surface of the compressor rotor disk **1120**. Each of the blades **1110** has a dovetail part **1112** which is fastened to the compressor rotor disk **1120**.

Vanes (not shown) fixed to the housing are respectively positioned between the rotor disks **1120**. Unlike the rotor disks, the vanes are fixed to the housing and do not rotate. The vane serves to align a flow of compressed air that has passed through the blades **1110** of the compressor rotor disk **1120** and guide the air to the blades **1110** of the rotor disk **1120** located on the downstream side.

The fastening method of the dovetail part **1112** includes a tangential type and an axial type. These may be chosen according to the required structure of the commercial gas turbine, and may have a generally known dovetail or fir-tree shape. In some cases, it is possible to fasten the blades to the rotor disk by using other fasteners such as keys or bolts in addition to the fastening shape.

The tie rod **1600** is arranged to pass through the center of the compressor rotor disks **1120** and turbine rotor disks **1320** such that one end thereof is fastened in the compressor rotor disk located on the most upstream side and the other end thereof is fastened by a fixing nut **1450**, wherein the tie rod **1600** may be composed of a single tie rod or a plurality of tie rods.

The shape of the tie rod **1600** is not limited to that shown in FIG. 2, but may have a variety of structures depending on the gas turbine. That is, as shown in the drawing, one tie rod may have a shape passing through a central portion of the rotor disk, a plurality of tie rods may be arranged in a circumferential manner, or a combination thereof may be used.

Although not shown, the compressor of the gas turbine may be provided with a vane serving as a guide element at the next position of the diffuser in order to adjust a flow angle of a pressurized fluid entering a combustor inlet to a designed flow angle. The vane is referred to as a deswirler.

The combustor **1200** mixes the introduced compressed air with fuel and combusts the air-fuel mixture to produce a high-temperature and high-pressure combustion gas. With an isobaric combustion process in the compressor **1100**, the temperature of the combustion gas is increased to the heat resistance limit that the combustor **1200** and the turbine **1300** components can withstand.

The combustor **1200** consists of a plurality of combustors, which is arranged in the housing formed in a cell shape, and includes a burner having a fuel injection nozzle and the like, a combustor liner forming a combustion chamber, and a transition piece as a connection between the combustor **1200** and the turbine **1300**, thereby constituting a combustion system of a gas turbine.

Specifically, the combustor liner provides a combustion space in which the fuel injected by the fuel nozzle is mixed with the compressed air of the compressor and the fuel-air mixture is combusted. Such a liner may include a flame canister providing a combustion space in which the fuel-air mixture is combusted, and a flow sleeve forming an annular space surrounding the flame canister. A fuel nozzle is coupled to the front end of the liner, and an igniter plug is coupled to the side wall of the liner.

On the other hand, a transition piece is connected to a rear end of the liner so as to transmit the combustion gas combusted by the igniter plug to the turbine side. An outer wall of the transition piece is cooled by the compressed air supplied from the compressor **1100** so as to prevent thermal breakage due to the high temperature combustion gas.

To this end, the transition piece is provided with cooling holes through which compressed air is injected into and cools the inside of the transition piece and flows towards the liner.

The air that has cooled the transition piece flows into the annular space of the liner and compressed air is supplied as a cooling air to the outer wall of the liner from the outside of the flow sleeve through cooling holes provided in the flow sleeve so that both air flows may collide with each other.

In the meantime, the high-temperature and high-pressure combustion gas from the combustor **1200** is supplied to the turbine **1300**. The combustion gas expands and collides with

and provides a reaction force to rotating blades of the turbine **1300** to cause a rotational torque, which is then transmitted to the compressor **1100** through the torque tube **1500**. Here, an excess of power required to drive the compressor **1100** is used to drive a generator or the like.

The turbine **1300** is basically similar in structure to the compressor **1100**. That is, the turbine **1300** is also provided with a plurality of turbine rotor disks **1320** similar to the compressor rotor disks **1120** of the compressor **1100**. Thus, the turbine rotor disk **1320** also includes a plurality of turbine blades **1310** disposed radially. The turbine blade **1310** may also be coupled to the turbine rotor disk **1320** in a dovetail coupling manner, for example. Between the blades **1310** of the turbine rotor disk **1320**, a turbine vane **1330** fixed to the housing is provided to guide a flow direction of the combustion gas passing through the blades.

The turbine vane **1330** is fixedly mounted within the housing by a vane platform **1340** (**1340a** and **1340b**) coupled to inner and outer ends of the turbine vane **1330**. The turbine vane platform coupled to the outer end is a turbine vane outer platform **1340a**, and the turbine vane platform coupled to the inner end is a turbine vane inner platform **1340b**. In a position facing the outer end of the rotating turbine blade **1310** on the inner side of the housing, a ring segment **1350** is mounted to form a predetermined gap with the outer end of the turbine blade **1310**.

The turbine vane **1330** is supplied with high-temperature and low-pressure combustion gases supplied from the combustor **1200**, and the turbine vane platform **1340**: **1340a**, **1340b** is cooled by low-temperature and high-pressure compressed air supplied from the compressor **1100**. At this time, if the low-temperature and high-pressure compressed air supplied to the turbine vane platform **1340** leaks toward the turbine vane **1330** where the high-temperature and low-pressure combustion gases flow, the power generation efficiency will decrease. To prevent such gas leakage, a conventional turbine vane platform sealing assembly **200**, as illustrated in FIG. 4, is installed on the turbine vane platform **1340**.

The conventional turbine vane platform sealing assembly **200** includes a first sealing unit **210**, a second sealing unit **220**, and a third sealing unit **230**. The first sealing unit **210** is formed in a first direction, the second sealing unit **220** is formed in a second direction intersecting the first direction, and the third sealing unit **230** is formed by bending in the second direction at a point where the first sealing unit **210** and the second sealing unit **220** are in contact.

As such, the conventional turbine vane platform sealing assembly **200** is installed such that the first sealing unit **210**, the second sealing unit **220**, and the third sealing unit **230** are laterally (circumferentially) inserted between a groove formed in one turbine vane platform **1340** and a groove formed in an adjacent turbine vane platform **1340**.

In the conventional turbine vane platform sealing assembly **200**, the first sealing unit **210**, the second sealing unit **220**, and the third sealing unit **230** are simply placed on one another in a sliding manner, so that the second sealing unit **220** and the third sealing unit **230** are likely to be accidentally detached when the turbine vane platform **1340** is removed during gas turbine maintenance. Therefore, there is a problem of poor reliability and ease of operation for operators.

Accordingly, the present disclosure proposes a turbine vane platform sealing assembly that can prevent accidental detachment from the turbine vane platform **1340**, thereby improving reliability and ease of operation during gas turbine maintenance.

FIG. 5 is a perspective view illustrating a turbine vane platform sealing assembly according to an embodiment of the present disclosure, FIG. 6 is a side view illustrating the turbine vane platform sealing assembly according to the embodiment of the present disclosure, FIG. 7 is a perspective view illustrating a second sealing member of the turbine vane platform sealing assembly, FIG. 8 is a perspective view illustrating a turbine vane platform sealing assembly installed on a turbine vane platform according to an embodiment of the present disclosure, FIG. 9 is a cross-sectional view illustrating a turbine vane platform sealing assembly installed on a turbine vane outer platform according to an embodiment of the present disclosure, and FIG. 10 is a cross-sectional view illustrating a turbine vane platform sealing assembly installed on a turbine vane inner platform according to an embodiment of the present disclosure

Referring to FIGS. 5 to 7, a turbine vane platform sealing assembly **2000** according to an embodiment of the present disclosure includes a first sealing member **2100**, a second sealing member **2200**, and a third sealing member **2300**. Although the turbine vane platform sealing assembly **2000** is illustrated in FIG. 5 as being inserted into adjacent turbine vane outer platforms **1340a** and **1340a**, as illustrated in FIGS. 8 to 10, the turbine vane platform sealing assembly **2000** may be inserted between adjacent turbine vane outer platforms **1340a** as well as between adjacent turbine vane inner platforms **1340b**. Hereinafter, the turbine vane outer platform **1340a** and the turbine vane inner platform **1340b** are collectively referred to as the turbine vane platform **1340**, and like reference signs are used for the turbine vane outer platform **1340a** and the turbine vane inner platform **1340b**.

The first sealing member **2100** is inserted into a first groove **1341** formed in a first direction of the turbine vane platform **1340**. To this end, the first sealing member **2100** is formed to extend in the first direction. The first direction may be an axial direction of a gas turbine (tie rod direction). The first sealing member **2100** is formed in a shape corresponding to the shape of the first groove **1341**. If the first groove **1341** is straight as in FIG. 4, the first sealing member **2100** is also formed straight, and if the first groove **1341** is straight with a curved end as illustrated in FIGS. 8 to 10, the first sealing member **2100** is also formed straight with a curved end.

The second sealing member **2200** is inserted into a second groove **1342** formed in a second direction intersecting the first direction. To this end, the second sealing member **2200** is formed to extend in the second direction. The second direction may be a radial direction with respect to an axis of a gas turbine. The second sealing member **2200** is formed in a shape corresponding to the shape of the second groove **1342**.

An end of the second sealing member **2200** fixedly contacts an upper surface of the first sealing member **2100**. Further, one side of the second sealing member **2200** is formed such that a portion of the third sealing member **2300** may be inserted and coupled thereto, which will be described with reference to FIG. 7.

Referring to FIG. 7, the second sealing member **2200** includes a sealing body **2210** and a sealing head **2220**. The sealing body **2210** is a plate-shaped metal member formed with a first thickness, and is a portion around which a bent part **2320** of the third sealing member **2300** to be described later is disposed. The sealing head **2220** is formed with a second thickness greater than the first thickness, and has an insertion groove **2221** at a portion that connects with the

sealing body 2210 such that a protruding tab 2330 of the third sealing member 2300 is inserted into the insertion groove.

The third sealing member 2300 is bent so that the third sealing member is partially disposed on the upper surface of the first sealing member 2100 and the third sealing member is partially coupled to the second sealing member 2200, thereby limiting circumferential movement of the third sealing member. To this end, the third sealing member 2300 includes an extension part 2310, a bent part 2320, and a protruding tab 2330.

The extension part 2310 is a part that extends in the first direction and is disposed on the upper surface of the first sealing member 2100. The bent part 2320 is a part that is formed by bending in the second direction at a point where the first sealing member 2100 and the second sealing member 2200 are in contact (referred to as a bend line). It is configured such that the sum of the thickness of the sealing body 2210 and the thickness of the bent part 2320 becomes the second thickness, which is the thickness of the sealing head 2220, so that when the bent part 2320 is disposed on the sealing body 2210, there is no step with the sealing head 2220 to facilitate assembly and disassembly.

The protruding tab 2330 is a tab formed to protrude from an upper surface of the bent part 2320 in a shape corresponding to the insertion groove 2221.

The extension part 2310 extends from the upper surface of the first sealing member 2100 to the bend line in the first direction, the bent part 2320 is disposed on the sealing body 2210, and the protruding tab 2330 is inserted into the insertion groove 2221 of the sealing head 2220, so that, as a whole, the third sealing member 2300 is coupled to the second sealing member 2200 to limit its circumferential movement.

In a gas turbine in which the turbine vane platform sealing assembly 2000 configured as described above is installed, when a turbine vane, a turbine vane platform, or a turbine vane platform sealing assembly is removed for maintenance and repair, the second sealing member and the third sealing member are coupled so that one or more of the sealing members are prevented from being accidentally detached from the turbine vane platform, thereby improving reliability and operability during the gas turbine maintenance and repair.

While the embodiments of the present disclosure have been described, it will be apparent to those skilled in the art that various modifications and variations can be made in the present disclosure through addition, change, omission, or substitution of components without departing from the spirit of the disclosure as set forth in the appended claims, and such modifications and changes may also be included within the scope of the present disclosure.

What is claimed is:

1. A turbine vane platform sealing assembly configured for installation in a gas turbine, the turbine vane platform sealing assembly comprising:

a first sealing member inserted into a first groove formed in a turbine vane platform in a first direction, the first sealing member extending in the first direction;

a second sealing member inserted into a second groove formed in a second direction intersecting the first direction of the turbine vane platform such that an end thereof contacts an upper surface of the first sealing member; and

a third sealing member provided so as to partially extend in the first direction while being partially bent in the second direction at a point where the first and second sealing members are in contact;

wherein

the second sealing member comprises: a plate-shaped sealing body formed with a first thickness, and a sealing head formed with a second thickness greater than the first thickness and having an insertion groove formed in a portion connecting with the sealing body,

the third sealing member comprises: an extension part formed to extend in a first direction and disposed on an upper surface of the first sealing member, a bent part formed by bending in a second direction at a point where the first sealing member and the second sealing member contact, and a protruding tab formed to protrude from an upper surface of the bent part and formed in a shape corresponding to the insertion groove;

the protruding tab is inserted into the insertion groove to restrict the movement of the third sealing member in a third direction lateral to the first direction and the second direction; and

the bent part has a first width in the third direction, and the protruding tab has a second width in the third direction that is less than the first width.

2. The turbine vane platform sealing assembly of claim 1, wherein the first sealing member is formed in a shape corresponding to that of the first groove.

3. The turbine vane platform sealing assembly of claim 1, wherein the second sealing member is formed in a shape corresponding to that of the second groove.

4. The turbine vane platform sealing assembly of claim 1, wherein the sum of the thickness of the sealing body and the thickness of the bent part is the same as the second thickness of the sealing head.

5. The turbine vane platform sealing assembly of claim 1, wherein the turbine vane platform is a turbine vane outer platform coupled to an outer end of a turbine vane.

6. The turbine vane platform sealing assembly of claim 1, wherein the turbine vane platform is a turbine vane inner platform coupled to an inner end of a turbine vane.

7. A turbine vane assembly, wherein a turbine vane is fixedly mounted within a housing by a turbine vane outer platform coupled to an outer end thereof and a turbine vane inner platform coupled to an inner end thereof, wherein at least one of the turbine vane outer platform and the turbine vane inner platform comprises a turbine vane platform sealing assembly configured for installation in a gas turbine, the turbine vane platform sealing assembly comprising:

a first sealing member inserted into a first groove formed in the at least one of the turbine vane outer platform and the turbine vane inner platform in a first direction, the first sealing member extending in a first direction;

a second sealing member inserted into a second groove formed in a second direction intersecting the first direction such that an end thereof contacts an upper surface of the first sealing member; and

a third sealing member provided so as to partially extend in the first direction while being partially bent in the second direction at a point where the first and second sealing members are in contact;

the second sealing member comprises: a plate-shaped sealing body formed with a first thickness, and a sealing head formed with a second thickness greater than the first thickness and having an insertion groove formed in a portion connecting with the sealing body,

the third sealing member comprises: an extension part formed to extend in a first direction and disposed on an upper surface of the first sealing member, a bent part formed by bending in a second direction at a point

11

where the first sealing member and the second sealing member contact, and a protruding tab formed to protrude from an upper surface of the bent part and formed in a shape corresponding to the insertion groove; the protruding tab is inserted into the insertion groove to restrict the movement of the third sealing member in a third direction lateral to the first direction and the second direction; and

the bent part has a first width in the third direction, and the protruding tab has a second width in the third direction that is less than the first width.

8. The turbine vane assembly of claim 7, wherein the first sealing member is formed in a shape corresponding to that of the first groove.

9. The turbine vane assembly of claim 7, wherein the second sealing member is formed in a shape corresponding to that of the second groove.

10. The turbine vane assembly of claim 7, wherein the sum of the thickness of the sealing body and the thickness of the bent part is the same as the second thickness of the sealing head.

11. A gas turbine comprising:

a compressor configured to suck and compress external air;

a combustor configured to mix fuel with the compressed air from the compressor and combust a mixture of the fuel and the compressed air; and

a turbine having turbine blades and turbine vanes mounted therein, the turbine blades being rotated by combustion gases from the combustor, wherein the turbine vanes each are fixedly mounted within a housing by a turbine vane outer platform coupled to an outer end thereof and a turbine vane inner platform coupled to an inner end thereof, wherein at least one of the turbine vane outer platform and the turbine vane inner platform comprises a turbine vane platform sealing assembly, the turbine vane platform sealing assembly comprising:

a first sealing member inserted into a first groove formed in the at least one of the turbine vane outer platform and the turbine vane inner platform in a first direction, the first sealing member extending in a first direction;

a second sealing member inserted into a second groove formed in a second direction intersecting the first direction such that an end thereof contacts an upper surface of the first sealing member; and

a third sealing member provided so as to partially extend in the first direction while being partially bent in the second direction at a point where the first and second sealing members are in contact;

wherein:

the second sealing member comprises: a plate-shaped sealing body formed with a first thickness, and a sealing head formed with a second thickness greater than the first thickness and having an insertion groove formed in a portion connecting with the sealing body,

12

the third sealing member comprises: an extension part formed to extend in a first direction and disposed on an upper surface of the first sealing member, a bent part formed by bending in a second direction at a point where the first sealing member and the second sealing member contact, and a protruding tab formed to protrude from an upper surface of the bent part and formed in a shape corresponding to the insertion groove;

the protruding tab is inserted into the insertion groove to restrict the movement of the third sealing member in a third direction lateral to the first direction and the second direction; and

the bent part has a first width in the third direction, and the protruding tab has a second width in the third direction that is less than the first width.

12. The gas turbine of claim 11, wherein the first direction is an axial direction of the gas turbine, and the first sealing member is formed in a shape corresponding to that of the first groove.

13. The gas turbine of claim 11, wherein the second direction is a radial direction with respect to an axis of the gas turbine, and the second sealing member is formed in a shape corresponding to that of the second groove.

14. The gas turbine of claim 11, wherein the sum of the thickness of the sealing body and the thickness of the bent part is the same as the second thickness of the sealing head.

15. The turbine vane platform sealing assembly of claim 1, wherein the sealing head comprises a top portion, a first side portion and a second side portion, wherein:

the first side portion and the second side portion extend away from the top portion in the second direction to define the insertion groove, and

the protruding tab is positioned between the first side portion and the second side portion when the protruding tab is inserted into the insertion groove.

16. The turbine vane assembly of claim 7, wherein the sealing head comprises a top portion, a first side portion and a second side portion, wherein:

the first side portion and the second side portion extend away from the top portion in the second direction to define the insertion groove, and

the protruding tab is positioned between the first side portion and the second side portion when the protruding tab is inserted into the insertion groove.

17. The turbine vane platform sealing assembly of claim 11, wherein the sealing head comprises a top portion, a first side portion and a second side portion, wherein:

the first side portion and the second side portion extend away from the top portion in the second direction to define the insertion groove, and

the protruding tab is positioned between the first side portion and the second side portion when the protruding tab is inserted into the insertion groove.
